SIGN-SUPPORTING POLE CAP

Wayne F. Hall, Bloomington, Ind., assignor to Hall Sign and Post, Inc., Bloomington, Ind., a corporation of Indiana

Filed Nov. 20, 1962, Ser. No. 72,548

Term of patent 14 years

(Cl. D54—1)

Fig. 1.

Fig. 3.

Fig. 2.

I claim:

The ornamental design for a sign-supporting pole cap, as shown.
